(57) **CLAIM**

The ornamental design for a headphone boom arm, as shown and described.

DESCRIPTION

FIG. 1 is a top perspective view of a headphone boom arm showing the new design;

FIG. 2 is a bottom perspective view of the headphone boom arm of FIG. 1;

FIG. 3 is an outer top perspective view of the headphone boom arm of FIG. 1;

FIG. 4 is an inner top perspective view of the headphone boom arm of FIG. 1;

FIG. 5 is a top view of the headphone boom arm of FIG. 1;

FIG. 6 is a bottom view of the headphone boom arm of FIG.

1;

FIG. 7 is a front view of the headphone boom arm of FIG.

1;

FIG. 8 is a rear view of the headphone boom arm of FIG. 1;

FIG. 9 is an inner side view of the headphone boom arm of FIG. 1;

FIG. 10 is an outer side view of the headphone boom arm of FIG. 1;

FIG. 11 is an outer side view showing the headphone boom arm of FIG. 1 in an environment in which it may be used; and,
